US00D582612S

(12) **United States Design Patent**
Rutherford

(10) **Patent No.:** **US D582,612 S**
(45) **Date of Patent:** **** Dec. 9, 2008**

(54) **BIRDCAGE ATTACHMENT**

(75) Inventor: **Ryan Rutherford**, Belleville, NJ (US)

(73) Assignee: **JW Pet Company, Inc.**, Teterboro, NJ (US)

(**) Term: **14 Years**

(21) Appl. No.: **29/291,517**

(22) Filed: **Aug. 31, 2007**

Related U.S. Application Data

(60) Continuation-in-part of application No. 29/266,260, filed on Sep. 15, 2006, now Pat. No. Des. 554,299, which is a continuation-in-part of application No. 29/264,790, filed on Aug. 17, 2006, now Pat. No. Des. 554,298, and a continuation-in-part of application No. 11/245,556, filed on Oct. 7, 2005, and a continuation-in-part of application No. 11/182,380, filed on Jul. 15, 2005, now abandoned, which is a division of application No. 29/230,071, filed on May 16, 2005, now Pat. No. Des. 530,866, which is a division of application No. 29/180,987, filed on May 2, 2003, now Pat. No. Des. 508,589, which is a continuation-in-part of application No. 10/371,646, filed on Feb. 21, 2003, now Pat. No. 6,971,332, said application No. 11/182,380 is a continuation of application No. 10/371,646, filed on Feb. 21, 2003, now Pat. No. 6,971,332.

(57) **CLAIM**

The ornamental design for a birdcage attachment, as shown and described.

DESCRIPTION

FIG. 1 is a front perspective of the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines encircling the perches and post are portions of the article that form no part of the claimed design. The items shown in broken lines form no part of the claimed design.
